ALDEN B. STOCKWELL, OF NEW YORK, N. Y., SOLE SURVIVING ADMINISTRATOR OF THE ESTATE OF ELIAS HOWE, JR., DECEASED.

Design No. 3,835, dated February 1, 1870.

DESIGN FOR A MEDAL OF ELIAS HOWE, JR.

The Schedule referred to in these Letters Patent and making part of the same.

To all whom it may concern:

Be it known that I, ALDEN B. STOCKWELL, sole surviving administrator of the estate of ELIAS HOWE, Jr., of New York, in the county and State of New York, do hereby declare that ELIAS HOWE, Jr., during his life-time, did invent a new and original Design for Elias Howe, Jr., Medal; and I do hereby declare that the following is a full, clear, and exact description thereof, which will enable others skilled in the art to make and use the same, reference being had to the accompanying drawings, forming part of this specification.

The nature of this design is fully represented in the accompanying drawing, to which reference is made.

Having thus described the invention, I claim as new, and desire to secure by Letters Patent, as the invention of the above-named ELIAS HOWE, JR., deceased—

The design for a medal, as shown.

ALDEN B. STOCKWELL,
Surviving Administrator of the Estate of Elias Howe, Jr.
